UNITED STATES PATENT OFFICE.

JOHN R. CALDERON, OF CHICAGO, ILLINOIS.

ANCHOR PLATE.

Application filed August 25, 1922, Serial No. 584,165.

To all whom it may concern:

Be it known that I, JOHN R. CALDERON, a citizen of the United States, residing at Chicago, in the county of Cook and State 5 of Illinois, have invented certain new and useful Improvements in Anchor Plates, of which the following is a specification.

The present invention relates to anchor plates.

10 More particularly the present invention relates to means for anchoring railroad rails to the ties and has for one of its objects the provision of simple and efficient means which may be readily installed either on 15 new construction or with rails already in service.

A further object is to provide efficient anchoring means which are cheap to construct and install.

20 Further objects will appear as the description proceeds.

Referring to the drawings—

Figure 1 is a plan view of one embodiment of the present invention applied to a 25 rail and tie, an intermediate position in the installation of said embodiment being shown in dotted lines;

Figure 2 is a sectional view taken along the plane marked by the line 2—2 of Figure 1;

Figure 3 is a view in side elevation of the structure shown in Figure 1;

Figure 4 is a plan view of a modified form of the present invention;

35 Figure 5 is a sectional view taken along the line 5—5 of Figure 4;

Figure 6 represents a detail;

Figure 7 is a plan view of a modified embodiment of the present invention applied to 40 a rail;

Figure 8 is a sectional view taken along the plane marked by the line 8—8 of Figure 7;

Figure 9 is a sectional view taken along the plane marked by the line 9—9 of Figure 7;

Figure 10 is a plan view of another embodiment of the present invention; and

50 Figure 11 is a sectional view taken along the line 11—11 of Figure 10.

The numeral 10 indicates a railway tie and the numeral 11 indicates a rail supported thereby. The anchor plate for holding the rail 11 securely on the tie 10 is 55 indicated by the numeral 12.

The rail 11 is provided with the flanges

13—13, which flanges constitute the base portion of the rail. The anchor plate 12 is provided with the bed portion 14 adapted to underlie and carry the rail 11. Said 60 anchor plate is preferably provided with longitudinally extending shoulders 12'—12' spaced apart a distance substantially equal to the width of the base of rail 11. Said anchor plate 12 is also provided at diagonally 65 opposed corners with a pair of upstanding members 15—15, which are undercut as indicated by the numerals 16—16 to provide parallel walls spaced apart a distance substantially equal to the width of 70 the base of the rail, that is to say, in substantial alignment with the inner walls of shoulders 12'—12'. The members 15—15 are provided with the overhanging portions 17—17, the inwardly facing edge 18 of one 75 of said portions 17 being arranged in substantial parallelism with a corresponding edge 18 of the opposed overhanging portion 17. The parallel walls 18—18 should lie at an angle to the undercut surfaces 16—16 80 and should be spaced apart a sufficient distance to receive between them the base of the rail 11. The overhanging portions 17—17 are of tapering conformation, being wider at the ends of the anchor plate and 85 decreasing toward the other ends of said overhanging portions 17—17, the wide end of one portion 17 being spaced longitudinally from the wide end of the other portion 17. The lateral members 15—15 may 90 be provided with spike holes 19—19 for receiving spikes 20—20 for holding the anchor plate in place.

The functions of the embodiment of the present invention illustrated in Figures 1 to 95 3 will be clear without detailed explanation. It may be stated, however, that the anchor plate is placed on the base of the rail in non-parallel relation with said rail in a position wherein the parallel edges 18—18 receive between them the flanges 13—13 of the rail. The anchor plate is then turned to a position in alignment with the rail whereby the overhanging portions 17—17 overlie the edges of said flanges. Spikes 20—20 may 100 now be driven into the ties through the spike holes 19—19. The anchor plate will be secured against skewing effect by the spikes 20 and shoulders 12'—12' and the anchor plate and therefore the rail will be 110 securely held to the tie.

The embodiment illustrated in Figures 4

to 6 inclusive combines the advantages of the anchor plate shown in Figures 1 to 3 with the advantages of bracing members for the rail, the embodiment illustrated in 5 Figures 4 to 6 being particularly useful on curves, where heavy side stresses are applied to the rail.

In the embodiment illustrated in Figures 4 to 6, the anchor plate is indicated by the 10 numeral 22, said anchor plate having the laterally extending members 23—23 extending from opposite sides of said anchor plate. Said members 23—23 are provided with braces 24—24 adapted to engage the opposite sides of the rail and to resist lateral stresses which are applied to said rail in service. Each of the braces 24—24 is recessed as indicated by the numerals 25—25, to provide holes for wedges 26—26, which 15 wedges are adapted to have wedging engagement between the flanges 13—13 of the rail and the braces 24—24. Spike holes 27—27 are provided in the members 23—23 for receiving spikes 28—28, which spikes 25 hold the wedges 26—26 firmly in position. The members 23—23 may be provided with raised portions 29—29 providing abutment means for said spikes 28—28 on the sides opposite said wedges 26—26. Spike holes for 30 receiving spikes 30—30 may be provided at positions adjacent to the side edges of the rail, and spike holes 31—31 may be provided for receiving spikes 32—32, which spikes 32—32 are placed to effectually resist any 35 skewing effects of the anchor plate. Shoulders 12—12' will also resist tendency toward such skewing effects.

The braces 24—24 have parallel side edges 33—33 spaced apart a sufficient distance to 40 receive between them the base of the rail 11. The embodiment shown in Figures 4 to 6 is mounted upon a rail in a manner similar to that described in connection with Figures 1 to 3, that is to say, the anchor plate is turned 45 to a position whereby the base of the rail may be mounted between the edges 33—33 of the braces 24—24, after which the anchor plate is turned to a position in which the ends of the braces 24—24 abut against the 50 web of the rail. The wedges 26—26 may then be mounted in the recesses 25—25 and spikes 28—28 may be driven into the tie, whereby to hold the wedges 26—26 in position.

55 Referring now to the embodiment illustrated in Figures 7 to 9, a structure is provided wherein a lateral brace for the rail is provided on only one side of said rail.

As shown in Figure 7, the anchor plate, 60 which in that figure is indicated by the numeral 22, is provided with a pair of laterally extending members 23—23 extending from opposite sides of the anchor plate and spaced longitudinally of the rail. Only one 65 of said laterally extending members 23 is

provided with a brace 24, the other laterally extending member being provided with only the undercut hold-down member 23', which functions in a manner similar to the members 15—15 discussed above in connection with Figures 1, 2 and 3. The brace 24 and the hold-down member 23' have parallel side edges 33—33 spaced apart a sufficient distance to receive between them the base of the rail 11. The brace 24 is recessed, as indicated by the numeral 25', to provide a hole for the wedge 26', which wedge is adapted to have wedging engagement with the flange 13 of the rail and said brace 24. A spike 28' holds the wedge 26' firmly in position in a manner similar to the action of the spike 28 used in the form of the invention illustrated in Figures 4 to 6. Other spikes 28'' and 31' cooperate with the shoulders 12' to hold the anchor plate against 85 skewing movement relative to the rail.

According to the embodiment illustrated in Figures 10 and 11, the laterally extending members 23—23 are provided with braces 29—29 for engaging both sides of the rail 11. Said braces 29—29 are undercut, in the manner described in connection with the members 15—15 of Figures 1 to 3, to engage the flanges 13—13 of the rail 11. Said braces 29—29 are adapted to engage the two sides of the rail and resist lateral strains applied to said rail. The braces 29—29 have parallel edges 33 which receive the base of the railroad rail in a manner which will be clear from the description of the preceding figures. Suitable spikes will cooperate with the shoulders 12—12' to prevent skewing of the anchor plate during service.

The described embodiments of the present invention have been chosen merely for the purpose of illustration and should not be considered in a limiting sense. Many modifications will occur to those skilled in the art. It is intended in this patent to cover all such modifications that fall within the scope of the invention as defined by the appended claims.

I claim:

1. An anchor plate comprising a bed portion having a pair of shoulder means for enclosing the base of a rail, said bed portion having a pair of overhanging members adapted in one position of said bed plate to receive between them the base of the rail and in another position to overlie said base.

2. An anchor plate comprising a bed portion having a pair of shoulder means for enclosing the base of a rail, members projecting upwardly from said bed portion, said members having a pair of opposed parallel walls and a second pair of opposed parallel walls at an angle to said first mentioned pair, said second pair of parallel walls adapted to overlie and hold the base of a railroad rail.

3. In combination, a tie, a rail, and an anchor plate, said anchor plate comprising a portion adapted to be mounted between said tie and said rail, said portion having a pair of shoulder means for enclosing the base of said rail and having upwardly projecting members adapted in one position of said anchor plate to receive between them the base of said rail and in another position 10 of said anchor plate to overlie and hold said rail.
4. In combination, a tie, a rail, and an anchor plate, said anchor plate comprising a portion adapted to be mounted between 15 said tie and said rail, said portion having a pair of shoulder means for enclosing the base of said rail and having upwardly projecting members adapted in one position of said anchor plate to receive between them 20 the base of said rail and in another position of said anchor plate to overlie and hold said rail, and spikes for holding said anchor plate in said latter mentioned position.
5. In combination, a railroad rail having 25 a web, a railroad tie, and anchoring means for said rail and tie, said anchoring means comprising a bed portion adapted to underlie said rail and upwardly projecting members adapted in one position to receive between them the base of said rail and in another position to overlie the base of said 30 rail, one of said upwardly projecting members comprising a web supporting member, said web supporting member being provided 35 with a recess, and a wedge located between said web supporting member and the base of said rail.
6. In combination, a railroad rail having a web, a railroad tie and anchoring means 40 for said rail and tie, said anchoring means comprising a bed portion adapted to underlie said rail and upwardly projecting members adapted in one position to receive between them the base of said rail and in another position to overlie the base of said 45 rail, one of said upwardly projecting members comprising a web supporting member, said web supporting member being provided with a recess, and a wedge located between 50 said web supporting member and the base of said rail, and a spike for performing the dual function of holding said wedge in position and holding said anchoring means in engagement with said tie.
- 55 7. An anchor plate, comprising a bed portion having a pair of shoulder means for enclosing the base of a rail, said bed portion
- having a pair of overhanging members adapted in one position of said bed plate to receive between them the base of the rail 60 and in another position to overlie said base, one of said overhanging members comprising means for supporting a rail web.
8. In combination, a rail, a tie, and anchoring means for said rail and tie, said 65 anchoring means comprising a bed portion and upwardly projecting means adapted in one position of said anchoring means to receive between them the base of said rail and in another position to overlie said rail, one 70 of said upwardly projecting means comprising web supporting means, said web supporting means being provided with a recess and a wedge within said recess slidable 75 transversely of the web.
9. In combination, a rail, a tie, and anchoring means for said rail and tie, said anchoring means comprising a bed portion and upwardly projecting means adapted in one position of said anchoring means to receive 80 between them the base of said rail and in another position to overlie said rail, one of said upwardly projecting means comprising web supporting means, said web supporting means being provided with a recess 85 and a wedge within said recess slidable transversely of the web, and a spike abutting against said wedge to prevent the escape of said wedge.
10. In combination, a rail, a tie, and anchoring means for said rail and tie, said anchoring means comprising a bed portion, upwardly projecting means adapted in one position of said anchoring means to receive 90 between them the base of said rail and in another position to overlie said rail, one of said upwardly projecting means being provided with a recess and a wedge within said 95 recess slidable transversely of the web.
11. In combination, a rail, a tie, and anchoring means for said rail and tie, said anchoring means comprising a bed portion, upwardly projecting means adapted in one position of said anchoring means to receive 100 between them the base of said rail and in another position to overlie said rail, one of said upwardly projecting means being provided with a recess and a wedge within said 105 recess slidable transversely of the web, and a spike abutting against said wedge to prevent the escape of said wedge.

Signed at Chicago, Illinois, this 18th day of August, 1922.

JOHN R. CALDERON
